(57) **CLAIM**

The ornamental design for a cable strut for guiding audio, video, and power cables, as substantially shown and described.

DESCRIPTION

FIG. 1 is a front perspective view of a cable strut for guiding audio, video, and power cables;

FIG. 2 is a back perspective view thereof;

FIG. 3 is a front view thereof;

FIG. 4 is a back view thereof;

FIG. 5 is a left side view thereof, the right side view being a mirror image thereof;

FIG. 6 is a top view thereof; and,

FIG. 7 is a bottom view thereof.

The broken lines shown represent unclaimed subject matter and form no part of the claimed design.
